UNITED STATES PATENT OFFICE

2,526,382

WATER DISPLACER STARTER FOR OUTLET SIPHONS

William J. McGinnis, Philadelphia, Pa.

Application June 6, 1946, Serial No. 674,805

2 Claims. (Cl. 4—47)

1

My invention relates to new and useful water displacer starters for outlet siphons and the like and has for one of its objects to simplify the construction of the control means for the outlet of tanks used for supplying a predetermined amount of liquid, such as water, to a location of use, such as the flush bowl of a toilet.

Another object of the invention is to employ a siphon as a part of the outlet from a liquid tank and provide unique means, including a ball cock valve and its control float, to start the siphonic action after an initial manual operation and thereafter automatically govern the completion of the siphonic action and the shutting off of the water supply to the tank.

A further object of this invention is to provide a device of the kind mentioned that permits the use of a narrower tank than usual in devices of this character with the accruing advantage of occupying less space sidewise.

A still further object of the present invention is to provide a novel valve operating mechanism.

With the above and other objects in view this invention consists of the details of construction and combination of elements set forth and then designated by the claims.

In order that those skilled in the art to which this invention appertains may understand how to make and use the same I will describe its construction in detail referring by numerals to the accompanying drawing forming a part hereof, in which—

Fig. 1 is a front elevation of a flush toilet structure to illustrate the connections and relationship between the parts.

Fig. 2 is an enlarged transverse vertical section of the tank showing the mechanism therein, in the shut-off position.

Fig. 3 is a similar view showing the mechanism in the starting position and in the full open position in dotted lines.

Fig. 4 is a section on the line 4—4 of Fig. 3.

Fig. 5 is a sectional view similar to Fig. 2 of a slightly different arrangement of the operating mechanism.

Fig. 6 is a side view, partly in section, of the float ball depressing trigger and stirrup.

Fig. 7 is a section on the line 7—7 of Fig. 6.

In carrying out my invention as herein embodied 10 represents a tank, in this case a flush tank, composed of the body or tank proper 11 with a cover 12 thereon. From the bottom of the tank leads an outlet pipe 13 to a flush bowl 14, for purposes of illustration, while an inlet pipe 15 leads to the upper portion of one side of the tank

2

where it is connected to a ball cock valve 16 having a shank 17 that projects through the tank side wall and to which the inlet pipe is actually attached, and constitutes the body of the valve, which can be small enough to save considerable metal.

As shown in Fig. 2, the ball cock valve has a plug 18 for controlling the flow of fluid through the valve and to the refill pipe 19 leading from the valve to a location adjacent the bottom of the tank. Cooperating with the valve plug 18 is a valve stem 20 controlled or actuated by the float ball rod 21 provided with a finger 22 for cooperation with a portion of the valve stem, such as a pin 23, Figs. 2 and 3, or an enlargement 24, Fig. 5. The rod 21 is pivoted at 25 and has a float 26 on its outer or free end. Said rod 21 has one or more notches 27 in longitudinal spaced relation along its upper surface, for a purpose to be presently described.

On the inside of the tank is a siphon 28 having the outlet leg connected to the outlet pipe 13 with the inlet leg terminating adjacent the bottom of the tank. An operating shaft 29 is journaled in the front wall of the tank and a bearing 30 on the siphon 28. The outer end of the shaft 29 projects through an escutcheon 31 fixed on the outside of the front wall of the tank and provided with shoulders 32 and 33 to limit the movements of a handle 34 fastened to the outer end of said shaft 29. The handle 34 should be heavy enough to return it to a normally perpendicular position but if not an additional weight 35 is fixed to the shaft, which weight will be sufficiently hefty to rotate the shaft with any associated elements for urging the handle to the pendant position.

On the shaft 29 directly above the rod 21 is fixed a float ball depressing trigger 36 that may have a longitudinal channel 37 in a portion of its underside for registration with the rod 21 and forming a contact edge 38, Fig. 6, for engagement with the notches 27, under certain conditions to be presently described. A stirrup 39 is swingingly connected to the depressing trigger 36 and hangs from the latter to partially surround the rod 21 and cooperate therewith to limit the descent of the rod 21 and its float 26.

In the structure illustrated in Fig. 5 there is a secondary member 40 associated with the depressing trigger. Said secondary member directly operates the ball cock valve by being attached to or formed with the valve stem 20. The secondary member 40 has an elongated aperture 41 to permit a to-and-fro movement of said second-

ary member over the shaft 29 and also has an arcuate slot 42 into which projects a pin 43 carried by the depressing trigger 36.

In operation, when the float 26 is raised by the liquid in the tank as the water level reaches the location 44 in Fig. 2, said float, through the medium of the rod 21, finger 22, pin 23 and valve stem 20, will close the ball cock valve 16 and shut off the flow of liquid to the tank. To empty the tank, the handle 34 is moved to the left, according to the illustration herein. This will rotate the shaft 29 and the depressing finger 36 until it forces the rod 21 and float 26 downward causing the float to be submerged and at the same time partly opens the ball cock valve. The water displaced by the float plus the water entering through the ball cock valve will raise the water level to the position 45, Fig. 3, and fill the crown of the siphon so that water will flow from the tank by the siphonic action. During the initial operation or upon the actuation of the handle 34, the edge 38 of the depressing trigger 36 will enter one of the notches 27 and because of the buoyancy of the float the parts will temporarily remain in the locked position. This also opens the ball cock valve 16 so that water enters the tank through the refill tube 19.

As the water level descends to a point about or just below that indicated at 46, Fig. 3, the rod 21 will be released from the depressing trigger and descend with the water until the level 47, Fig. 3, is reached. The rod and float will then be suspended by the stirrup 39 as the water level recedes further.

The releasing of the depressing trigger permits it to be returned to the substantially horizontal position as the handle assumes its vertical location and when the water level descends below the short leg of the siphon the siphonic action will cease and the tank will be practically empty. Water will continue to flow through the ball cock valve and refill tube into the tank and gradually refill the latter. When the float is returned to its position by the rise of the water level, the ball cock valve will be closed to shut off the water supply to the tank and the apparatus will be ready for the next operation.

Of course I do not wish to be limited to the exact details of construction herein shown and described as these may be varied within the scope of the appended claims without departing from the spirit of my invention.

Having described my invention what I claim as new and useful is:

1. A water displacer starter for an outlet siphon comprising a tank having an inlet at one side adjacent the top thereof and an outlet leading from the bottom of said tank, a ball cock valve connected to said inlet and including a valve stem, a float rod having its inner end pivoted adjacent the ball cock valve below the same, a float on the outer free end of said rod, a finger fixed to said rod and having a longitudinal slot therein and projecting along side of the stem of the ball cock, a pin on said stem projecting into the slot in the finger whereby motion is transmitted from said float rod to the valve stem, a siphon within the tank in the region of the outer free end of the float rod and having one leg connected to the tank outlet and the other leg terminating adjacent the interior surface of the bottom of said tank, a shaft bearing on said siphon, a shaft having one end journalled in said bearing and the other end projecting through and journalled in one of the upright walls of said tank, a handle on the projecting end of the shaft to rotate the same, and a depressing trigger fixed on said shaft and engaging the outer end portion of the float rod to swing said float rod downwardly when the handle is actuated, said float rod having a notch with which the depressing trigger registers temporarily upon depression of the float rod.

2. The water displacer starter for an outlet siphon according to claim 1, in combination with a U-shaped stirrup having its upper ends pivoted to the depressing finger below the shaft and partially surrounding the outer end portion of the float rod to limit its descent.

WILLIAM J. McGINNIS.
